(57) **CLAIM**

The ornamental design for a pebble shaped dispenser for notes, as shown and described.

DESCRIPTION

FIG. 1 is a perspective view showing the new design for a pebble shaped dispenser for notes;

FIG. 2 is a top view thereof;

FIG. 3 is a front view thereof;

FIG. 4 is a back view thereof;

FIG. 5 is a right side view thereof;

FIG. 6 is a left side view thereof; and,

FIG. 7 is a bottom view thereof.

The broken lines showing the slot in the top and internal features in FIGS. 1, 2, 4, 5, and 6 are included to show features that form no part of the claimed design.
